(No Model.)

C. W. HARMON,
PENHOLDER.

No. 595,389.

Patented Dec. 14, 1897.

UNITED STATES PATENT OFFICE.

CHARLES W. HARMON, OF PITTSBURG, PENNSYLVANIA.

PENHOLDER.

SPECIFICATION forming part of Letters Patent No. 595,389, dated December 14, 1897.

Application filed March 30, 1897. Serial No. 629,926. (No model.)

To all whom it may concern:

Be it known that I, CHARLES W. HARMON, a citizen of the United States, residing at Pittsburg, in the county of Allegheny and State of Pennsylvania, have invented or discovered a new and useful Improvement in Penholders, of which the following is a full, clear, and exact description, reference being had to the accompanying drawings, forming part of this application, in which—

Figure 1 is a perspective view of a penholder made in accordance with my invention. Fig. 2 is a front elevation thereof, partly broken away, showing the guide-rod extended. Fig. 3 is a similar view showing the guide-rod retracted. Fig. 4 is a central longitudinal section. Fig. 5 is a cross-section, on an enlarged scale, taken on the line V V of Fig. 4.

My invention relates to ruling attachments for penholders; and it consists of an extensible rod mounted longitudinally in the body portion of the holder adapted to be extended for use against a straight-edge or other suitable guide and so arranged as to be adjacent to the pen without contact, thereby avoiding any tendency of the ink to run.

Referring to the drawings, 2 is the main stem of the holder, upon which is mounted at the end the point-embracing ferrule 3, firmly and tightly secured on the end of the stem 2 and flush with its outer surface. A recess 4 extends from the end of the stem backwardly for part of the length of the ferrule 3, which recess is made by reducing the diameter of the stem sufficiently to permit of the entrance of the pen-point 5, which is firmly held therein. An outer surrounding ferrule 6, of hard rubber or other suitable material, embraces the ferrule 3 and part of the stem 2 for a portion of its length and serves as a convenient hold for the fingers. Along one side of the interior is a longitudinal channel 7 for almost the full length of the ferrule 6, a portion of which, 7', extends clear through to the exterior and constitutes a slot. Mounted in the longitudinal channel is a sliding rod 8, provided with a small lug 9, projecting out through the slot 7, by which the rod is extended or withdrawn, the extremities of the slot serving to limit the movement of the rod by reason of the lug 9 coming into contact therewith. When withdrawn, the rod is entirely within the outer ferrule, as shown in Fig. 3, and when extended the point of the rod corresponds to the point

of the pen, as shown in Figs. 1 and 2, so that 55 when placed upon the paper and against a guiding edge the point of the pen and of the rod will touch the paper simultaneously and the pen-point will be held away from contact with the straight-edge while a parallel line is 60 easily drawn.

By changing the angle of the penholder the line may be drawn at varying distances from the straight-edge, and a further feature of advantage is the ease of observing the line. 65

Other features of advantage will be observed by the user of my penholder, and while it is constructed for the purpose of ruling lines the efficiency as an ordinary penholder is in no manner impaired, as the presence of 70 the rod when withdrawn offers no impediment or unusual enlargement of the penholder whatever. By reversing the pen-point to the other side the holder may be easily adapted for left-hand use. 75

I claim—

1. In a penholder consisting of a stem and a pen-embracing ferrule flush with the outer surface of the stem; an outer cylindrical ferrule provided with an internal longitudinal 80 channel slotted through for part of its length and an extensible guide-rod mounted in such channel in the body of the ferrule with a lug extending through the slot, substantially as set forth. 85

2. A penholder consisting of a stem, a pen-embracing ferrule mounted on the end thereof, an outer ferrule inclosing the point-ferrule and part of the stem and provided with an internal longitudinal channel and an extensible guide-rod mounted in such channel in the body of the ferrule, substantially as set forth. 90

3. A penholder consisting of a stem, a pen-embracing ferrule mounted on the end thereof, an outer ferrule inclosing the point-ferrule and part of the stem provided with an extensible guide-rod mounted in the body of the ferrule and provided with an operating-lug extending through a slot in the side of 100 the ferrule, substantially as set forth. 95

In testimony whereof I have hereunto set my hand this 24th day of February, 1897.

CHARLES W. HARMON.

Witnesses:

PETER J. EDWARDS,
C. M. CLARKE.
